UNITED STATES PATENT OFFICE.

HERBERT RENNO OLCOTT, OF PORTLAND, OREGON, ASSIGNOR TO JOHN S. BEALL, OF PORTLAND, OREGON.

CULVERT-JOINT.

1,227,187.

Specification of Letters Patent.

Patented May 22, 1917.

Application filed November 29, 1915. Serial No. 63,958.

To all whom it may concern:

Be it known that I, HERBERT RENNO OLCOTT, a citizen of the United States, residing at Portland, in the county of Multnomah and State of Oregon, have invented certain new and useful Improvements in Culvert-Joints, of which the following is the specification.

This invention relates to a method and apparatus for uniting two sections of metallic or other piping, and particularly to a method and apparatus for uniting two sections of metallic culvert, in an economical, rigid, strong and secure fashion.

It is an object of the invention to provide a joint for uniting two culvert or other sections, which is simple, economical, easy to operate and easy to attach, serving to rigidly unite the two sections when attached.

Other objects and advantages of the invention will appear as the description to follow proceeds.

In the drawings:

Figure 1 is an elevation of two culvert sections, butt-ended in position for the attachment of the joint.

Fig. 2 is an elevation partly broken out showing the joint in process of attachment.

Fig. 3 is a similar view, illustrating the process of attachment.

Fig. 4 is a similar view illustrating the joint attached.

Fig. 5 is a perspective view of the joint.

In the drawings: 1 represents a corrugated culvert section of familiar form. The joint of my invention comprises a corrugated split-ring 2 which is longer than the circumference of either culvert section and which is provided with fastening straps 3 seated in the troughs of adjoining corrugations and projecting beyond the adjacent end of the split-ring 2. Upon the opposite end of the split-ring 2 I provide a bar 4 fastened, as by rivets 5, to the crests of adjoining corrugations. In attaching the device, the culvert sections are butt-ended, as indicated in Fig. 1. The split-ring 2 is moved endwise along one of them, being opened sufficiently to permit this, and is seated as shown in Fig. 2 with its corrugations interlocked upon the culvert sections 1, and the straps 3 lying in adjoining troughs and passing

under the bar 4. Thereafter, a chain, such as 5, is placed about the joint and twisted by a bar, such as 6', to tighten the joint about the culvert sections. After the chain has been tightened sufficiently to securely lock the joint in position upon the culvert sections, the straps 3 are bent over, as shown at 6 (Fig. 4) to lock the joint, and the two culvert sections will be found to be engaged in an absolutely rigid and secure fashion. It is, of course, obvious that other means besides the bar and chain might be used to tighten the joint, for instance, a peavey. Any adequate means for achieving this tension being equally within the scope of the invention.

Having now described my invention I claim:

1. A culvert comprising a pair of full cylindrical culvert sections arranged end to end and a joint comprising a strip corrugated throughout its length surrounding the adjacent ends of the sections and overlapped upon itself whereby said overlapped portions form a substantially watertight joint, and means to maintain said joint in gripping relation with the culvert sections.

2. A culvert comprising a pair of corrugated culvert sections arranged end to end, and a split culvert section corrugated throughout its entire length larger than said first mentioned culvert sections arranged in overlapping registering and gripping relation upon both adjacent ends, and means to maintain said gripping relation.

3. A culvert comprising a pair of corrugated culvert sections butt-ended, a split corrugated ring having a bar substantially removed from one circumferential end and secured to the ring, a malleable strip secured upon the other circumferential end, said ring being clamped upon said butt-ended adjacent culvert ends and secured by said malleable strip and bar.

In witness whereof, I hereunto subscribe my name to this specification in the presence of two witnesses.

HERBERT RENNO OLCOTT.

Witnesses:

A. L. GAGE,
JNO. S. BEALL.
